SHOE RACK

Albert S. Darby, Abilene, Tex.

Application July 18, 1946, Serial No. 684,499

12 Claims. (Cl. 211—35)

1

This invention relates to shoe racks, and is an improvement over my copending application, Serial Number 645,331, filed February 4, 1946, for a shoe rack, which has become abandoned.

An object of this invention is to provide an improved shoe rack for supporting shoes from a wall or other suitable support.

Another object of this invention is to provide a shoe rack having individual shoe supporting members which may be inserted into a shoe and which are particularly adapted to not only support or suspend the shoe, but also to form a substantial shoe tree to support the normal shape of the shoe while it is being supported on the rack.

Another object of this invention is to provide an improved shoe rack of the type to be herein-after described, having individual shoe supporting members constructed out of a single length of wire engageable on a supporting bar at an angle to the vertical, the supporting bar being so constructed that the angle of inclination of the shoe supporting members may be reversed by simply inverting the supporting bar.

Still another object of this invention is to provide a shoe rack having a supporting bar and shoe supporting members removably engaging the bar in a selected direction of inclination.

With the above and other objects in view, my invention consists in the arrangement, combination and details of construction disclosed in the drawings and specification, and then more particularly pointed out in the appended claims.

In the drawings,

Figure 1 is a front elevation of a shoe rack constructed according to an embodiment of this invention,

Figure 2 is a vertical section taken on the line 2—2 of Figure 1,

Figure 3 is a vertical section of a modified form of supporting bar,

Figure 4 is a fragmentary side elevation of a modified form of shoe supporting member, and

Figure 5 is a fragmentary front elevation of the rack of Figure 1 with the shoe supporting member in the opposite direction.

Referring to the drawings, the numeral 10 designates generally a horizontal supporting bar constructed according to an embodiment of this invention on which are attached a plurality of shoe supporting members designated generally by the numeral 11. The bar 10 is adapted to be horizontally supported and if thin, may be disposed on edge with its wide faces upright or vertical fixedly attached to a vertical support 12

2

as a door or wall, or other suitable place where shoes are generally stored for a short time as in a home or on display. The shoe supporting members are usually disposed on the bar in pairs and in Figure 1 the bar 10 is shown as supporting two pairs. Each of the shoe supporting members 11 is of similar construction formed from a length of wire having a certain degree of resiliency while maintaining a substantial degree of rigidity.

10 The supporting member 11 is formed of a single length of wire bent upon itself to provide a substantially inverted U-shaped member or oppositely tapered open loop sufficiently narrow widthwise to enter or fit into a shoe crosswise at the toe and vamp or instep having the bight 14 thereof at the uppermost end, the bight being relatively short or narrow, centrally located horizontally and of a straight configuration, and the upper half side portions or arms 15 of the 15 U-shaped member being disposed in a downwardly divergent relation for substantially half the length or height of the member or loop. The arms 15 are then convergent or inclined inwardly toward each other to form a pair of oppositely disposed downwardly converging arms or lower side portions 16. The lower end of one arm 16 terminates where the arms or side portions are adjacent or come together and is the end of the length of the wire, and the other arm 16 is bent at its lower end or junction point with the first arm at substantially a right angle to the supporting member 11 or horizontally at an acute angle to the lower portion of the latter arm and in the same plane as the arms 15 and 16, to provide a base arm 17. The arm 17 is in turn bent at right angles upwardly, coplanar to or still in a plane common to the member 11, and reverted outwardly to form a gooseneck or laterally extended or offset inverted U-shaped hook 18, the lower end of the outer arm 19 terminating in the horizontal plane of portion 17 at the other end of the length of wire.

45 The free end of the first arm 16, being one end of the wire, is not attached to any part of the shoe supporting member 11, thus permitting the arms 15 and 16 to be stretched, bent or distorted to provide a certain degree of adjustment of the shoe supporting member 11 coplanar with or at an incline or angle to the base arm 17, hook or gooseneck 18 and outer arm 19 for engagement of parts 18 and 19 in openings or grooves at an angle or inclined, or vertically of the supporting bar 10 or to fit different sized shoes, yet being stiff enough to press outwardly at the sides

within the shoes to hold their shape while on the member 11.

There may be certain constructions of this shoe rack where it is desirable to secure this lower end of the one or first arm 16 and adjustment may be made by distorting the complete shape of the member 11. At this time the end of the first arm 16 may be secured to the lower end of the other or second arm 16 and base 17 by welding as at 21 or any other suitable attaching means, as shown in Figure 4.

The supporting bar 10 is formed of a suitably supported horizontal bar or an elongated, flat strip of metal, wood, plastic or any suitable material with its narrow edges at the top and bottom and its wide faces upright or vertical and is secured to the vertical supporting member 12 transversely thereof, by screws 20 or other suitable attaching means. The horizontally supported bar 10 is formed on each vertical side with oppositely disposed, aligned grooves or slots 22 which are vertical or inclined at an angle to the vertical whereby the arms of the inverted U-shaped hook 18 may engage in the grooves or slots 22 on opposite sides of the bar 10 with the bight at the top of the hook 18 over the top edge of bar 10 for supporting the shoe supporting member 11 at an angle or inclined position to the bar 10 or, with the grooves or slots 22 vertical, the member 16 may be vertical or bent at its juncture with the base 17 at such angle or inclined position. At certain times because of the particular location of the shoe rack, it may be desirable to have the members 11 inclined in the opposite direction or to extend upwardly to the right as in Figure 1, and at other times upwardly to the left as in Figure 5. To change the angle of the members 11, it is necessary only to slide the members 11 from the bar 10, remove the bar 10 from the wall 12 and reinstall the bar 10 in an inverted position or reversed end to end, whereupon the slots 22 will be inclined in the opposite direction and the members 11 may be again slipped into place.

By using a bar 10 as described above, the outer arm 19 of the hook 18 is engaged between the bar 10 and wall 12 in the inside slot 22. An alternative form or construction of the bar is shown in Figure 3, wherein the bar 10a is formed with an inclined or vertical bore 24 in lieu of the grooves 22 to receive the arm 19 therein and the hook 18 engaged over and against the front surface of the bar 10a and the bight of hook 18 over the top edge of the bar with the supporting member 16 vertical or bent from arm 17 at an angle or inclined position in either direction and supported and retained in position, whereupon the arm 19 does not contact the wall 12 at any time. The bar 10a may be reversed in the same manner as the bar 10 for changing the direction of the angle of the shoe supporting member 11.

A shoe rack of this kind may be mounted at any convenient location and when any number of shoe supporting members 11 are not used the members 11 may be readily slipped from the bar 10 or 10a, thereby providing more room as in a closet and eliminating unnecessary obstructions at other locations, and may just as readily be reinstalled when again desired.

I do not mean to confine myself to the exact details of construction herein disclosed but claim all variations falling within the purview of the appended claims.

What I claim is—

1. A shoe rack comprising an elongated hori-

zontal supporting bar, said bar formed with oppositely disposed spaced parallel inclined openings from top to bottom, and a shoe supporting member, said member formed of a length of wire bent upon itself to form a substantially inverted U-shaped shoe engaging portion and a coplanar inverted U-shaped bar engaging hook, said hook being slidable in said openings.

2. A shoe rack comprising an elongated horizontal supporting bar and a shoe supporting member slidably engaging said bar, said supporting bar formed with upright parallel openings extending through the top and bottom edges thereof, said shoe supporting member formed of a length of wire bent upon itself to form a substantially inverted U-shaped shoe engaging portion and an inverted U-shaped bar engaging hook coplanar with said shoe engaging portion and slidably engageable in said openings.

3. A shoe rack as set forth in claim 2 wherein one lower arm of said shoe engaging portion is secured to the lower end of the opposite arm thereof.

4. A shoe rack comprising an elongated supporting bar and a shoe engaging member engageable thereon, said bar formed with grooves on opposite sides thereof, said grooves disposed at an angle to the vertical, said shoe engaging member formed of a length of wire bent upon itself to form a substantially inverted U-shaped shoe engaging portion and an inverted U-shaped bar engaging hook, the arms of said hook slidably in said grooves.

5. A shoe rack comprising an elongated supporting bar and a shoe supporting member slidable thereon, said bar formed with bores therethrough, said bores being disposed at an angle to the vertical, said shoe engaging member formed of a length of wire bent upon itself to form a substantially inverted U-shaped shoe engaging portion and an inverted U-shaped bar engaging hook, the free arm of said hook slidable in said bore.

6. A shoe rack comprising an elongated horizontal bar and a shoe supporting member slidably engaging said bar, said supporting bar formed with vertically disposed openings, said shoe supporting member formed of a length of wire bent upon itself to form a substantially inverted U-shaped shoe engaging portion and an inverted U-shaped bar engaging hook on said shoe engaging portion slidably engageable in said openings.

7. A shoe rack comprising an elongated bar, said bar being formed with aligned grooves on opposite sides thereof, and a shoe supporting member formed of a length of wire having one end portion bent to form a shoe engaging loop with a horizontal portion at the bottom with an inverted U-shaped hook on its free end to slidably engage the grooves with the top bight portion thereof against the top edge of the bar.

8. A shoe rack comprising an elongated supporting bar disposed horizontally on edge, said bar being formed with spaced parallel aligned openings on opposite sides thereof, and shoe supporting members engageable with said bar, each of said members being formed with an inverted vertical loop having a portion extended horizontally at the bottom of the loop and an upwardly extending inverted hook at the free end of the horizontal portion having a bight at the top and side portions adapted to slidably and detachably engage over the top edge of the bar and with said openings.

9. A shoe rack comprising an elongated horizontal supporting bar formed with spaced parallel aligned grooves on opposite sides thereof, and a shoe supporting member engageable with said bar, said member being formed of a length of wire having one end portion bent upon itself to form a shoe engaging loop with a horizontal portion extending from the bottom of one side of the loop and the end of said horizontal portion bent to form an upwardly extending U-shaped hook, said horizontal portion and hook being in the same plane as the loop and said hook adapted to detachably engage in said grooves.

10. A shoe rack comprising a supporting bar disposed on edge in a horizontal position and having openings therein extending from top to bottom, and a shoe supporting member comprising a length of wire bent to form a loop with a bight at the top and sides brought together at the bottom, one side being bent from the bottom of the loop horizontally coplanar with the loop, then upwardly in spaced relation to the loop and finally downwardly in spaced relation to said upwardly bent portion to form an inverted hook adapted to engage over the bar at its top edge and with the downwardly bent portion slidably engageable with and extending into the opening and the upwardly bent portion against the front of the bar.

11. A shoe rack comprising an elongated horizontal supporting bar having opposite vertical surfaces and formed with spaced upright openings extending through its top and bottom edges and a shoe supporting member formed of a strand of wire bent to form a loop with its bight portion at the top and tapering in opposite directions with the lower portions thereof converging toward each other and then one portion bent horizontally and formed with an inverted hook at its free end coplanar with and spaced from 40

the loop for engagement over the top of the bar in said opening and against at least one face of the bar, said loop adapted to extend vertically or at an incline.

- 5 12. A shoe rack comprising a horizontal supporting bar disposed on edge and a shoe supporting member slidably engaging said bar, said bar being formed with spaced inclined parallel openings extending from top to bottom, said 10 member being formed of a length of bendable material bent upon itself to form an inverted substantially U-shaped shoe engaging portion with its sides brought toward each other at the bottom and the lower end of one side bent to 15 form an upwardly extending inverted hook at its free end to engage over the top edge of the bar and in openings thereof.
